UNITED STATES PATENT OFFICE.

VICTOR GUINZBURG, OF NEW YORK, N. Y., ASSIGNOR TO I. B. KLEINERT RUBBER COMPANY, A CORPORATION OF NEW YORK.

BABY PANTS OR DIAPER-COVER.

1,033,097.

Specification of Letters Patent. Patented July 23, 1912.

Application filed October 14, 1910. Serial No. 587,038.

To all whom it may concern:

Be it known that I, VICTOR GUINZBURG, a citizen of the United States, and a resident of the borough of Manhattan, city, county, 5 and State of New York, have invented certain new and useful Improvements in Baby Pants or Diaper-Covers, of which the following is a specification, accompanied by drawings.

10 This invention relates to baby pants, otherwise known as baby diaper covers, and the objects of the invention are to prevent escape of moisture therefrom.

In the construction preferred the pants 15 are securely confined about the child's legs and the edges of the crotch portion drawn upward tending thereby not only to hold the edges against the legs but also permitting the crotch to be substantially bagged.

20 The invention as embodied in the best form known to me is illustrated in the accompanying drawings, in which—

Figure 1 shows a front view with the flaps of the garment buttoned up; Fig. 2 is a 25 face view showing in full the baby pants flattened out with the flaps connected to each other, and showing in dotted lines the flaps disconnected and spread out.

The baby pants are substantially a one 30 piece garment which comprises a back B and front and side flap pieces C, C and D. Side flaps C have buttonholes E. Flap D is equipped with coöperating buttons G for connecting the flaps C, C to flap D as shown.

35 The garment is cut from one piece of material to shape substantially as shown being of least width at its crotch. From the crotch the garment widens upward front and back to form the legholes. The crotch H is preferably baggy to better inclose the diapers 40 when the garment is worn. The edges J of the leg openings K are preferably cut on a smooth curve as shown in Fig. 2. Drawing strings or tape L are run in the edges of the 45 legholes, for purposes presently described. When in use, the flaps of the garment are

buttoned as shown and said drawing strings or tape L are drawn upon and tied.

It will be seen that the finished garment when in use fits snugly around the crotch and widens upward to the top of the leg holes, 50 thence it narrows to the waist line. The back may be made adjustable by drawing strings tying together at M.

The tapes L from the crotch extend upward and outward, at front and back as plainly shown, and for this reason: the tightening of the tape, as shown in the figures, draws upward the edges of the crotch portion, in the direction of the arrows thus 55 forming the crotch portion into a baggy shape thereby better confining its contents and preventing escape of moisture. The tightening of the tape further results in the leg opening K being correspondingly contracted, this contracting confining the edges 60 to the leg more closely all around for the same object.

I prefer to make the garment of light-weight impervious wash-material thereby 65 rendering it hygienic, and easily laundried.

Of course by tape I intend to include any suitable drawing string or equivalent means for tightening the edges as explained.

I claim and desire to obtain by Letters 70 Patent the following:—

1. Impervious or moisture proof baby pants which when unfolded are substantially flat and which have side flaps and a front flap which at the vicinity of the crotch portion 75 widens forward and has means for securing it in front at points more widely apart than the crotch portion, whereby the crotch portion may be baggy and hold closely to the legs toward the front and drawing tapes 80 for tightening the edges of said crotch portion whereby the said tapes tend to draw said edges outward toward the front of the 85 crotch portion.

2. Impervious or moisture proof baby pants having a front flap which widens from 90 the crotch forward and is provided with

means for securing it with the edges of the crotch portion of the flap extended forward, upward and outward thereby tending to hold them against the leg of the wearer and means in addition to said securing means for drawing said edges upward and outward against the legs.

In testimony whereof I have signed this

specification in the presence of two subscribing witnesses. Dated this 13th day of Oct. 10 1910.

VICTOR GUINZBURG.
